[57] CLAIM

The ornamental design of a vanity mirror and cover for a vehicular sun visor, as shown and described.

DESCRIPTION

FIG. 1 is a perspective view of a vanity mirror and cover for a vehicular sun visor showing my new design with the cover in closed condition concealing the vanity mirror; and, FIG. 2 is a perspective view thereof with the cover in open condition exposing the vanity mirror.

The broken line showing of the vehicular sun visor shown in the drawing is for illustrative purposes only and forms no part of the claimed design.
